UNITED STATES PATENT OFFICE.

WILLIAM GRIKSCHET, OF DETROIT, MICHIGAN.

PRIMING-CUP.

1,353,584.

Specification of Letters Patent. Patented Sept. 21, 1920.

Application filed September 19, 1919. Serial No. 324,819.

To all whom it may concern:

Be it known that I, WILLIAM GRIKSCHET, a citizen of the United States of America, residing at Detroit, in the county of Wayne and State of Michigan, have invented certain new and useful Improvements in Priming-Cups, of which the following is a specification, reference being had therein to the accompanying drawings.

10 The invention relates to priming cups of that type in which the discharge of fluid from the cup is controlled by a valve having a threaded stem. It is the object of the present invention to provide a dust cap for 15 the cup, which when the valve is seated, will be securely held in engagement with the cup, but which permits of access to the cup when the valve is unseated. To this end the invention consists in the construction as 20 hereinafter set forth.

In the drawings:

Figure 1 is a longitudinal section through the cup showing the valve unseated and the cap removed;

25 Fig. 2 is a section in a transverse plane showing the valve seated and the cap in position.

A is a priming cup having a shank portion B terminating in a threaded nipple C. 30 D is a valve for controlling the discharge from the cup, which as specifically shown is in the form of a hollow stem having a threaded portion E engaging a correspondingly threaded portion in the shank B; also 35 the shoulder F for engaging the valve seat G and a lateral port H through the hollow stem below the shoulder F. Thus when the valve is seated, discharge of the liquid is prevented, but upon unseating the valve the 40 liquid will obtain access to the port H and will be discharged through the hollow stem.

Various constructions of dust-caps have been used in connection with priming cups, but these are usually held in engagement by 5 the use of springs. With the present construction the cap is attached to the handle for operating the valve and is so constructed that when the valve is unseated, the cap may be removed to uncover the cup, but when 0 the valve is at its seat will be locked upon the cup. As shown, the operating handle I is secured to the valve stem D by a knuckle

joint K, so it can be capable of angular movement, and L is a cap member mounted on the handle I and provided with a flange 55 M which when the valve is seated, telescopically engages with the upper edge of the cup A, as shown in Fig. 2. In this position the cap is held from disengagement from the cup and the handle is also held in upright position. To remove the cap the handle I is turned in a direction to unseat the valve and as soon as it has been adjusted a sufficient distance for the flange M to clear 60 the upper edge of the cup the handle may be turned upon the knuckle joint K into the position shown in Fig. 1. This will open access to the cup and will also open the valve so that the contents of the cup may be discharged.

To prevent complete detachment of either the cap or the valve stem, the latter is provided with a flange N at its inner end which engaging a shoulder O on the shank B will prevent further outward movement of the 75 stem.

What I claim as my invention is:

1. The combination with a cup and a valve controlling the discharge from said cup having threaded engagement therewith, of a 80 handle for operating said valve, and a cap for said cup mounted on said handle and adapted to be locked in engagement with the cup when the valve is seated.

2. The combination with a cup, of a valve 85 controlling the discharge from said cup having a threaded engagement therewith, a handle for operating said valve, a cap mounted on said handle, and a flange on said cup for telescopically engaging the upper edge of 90 said cup when the valve is seated, said flange clearing the cup when the valve is unseated to permit access thereto.

3. The combination with a cup, of a valve 95 controlling discharge from said cup having a threaded stem in engagement therewith, a handle for actuating said stem having a pivotal engagement therewith, and a cap mounted on said handle provided with a flange for telescopically engaging the upper 100 edge of said cup when the valve is seated and clearing said edge to permit swinging of the handle and cap when the valve is removed from its seat.

4. The combination with a cup having a hollow shank and a valve seat therein, of a valve having a hollow threaded shank engaging said hollow stem, a shoulder for engaging said valve seat, and a lateral aperture between said shoulder and threaded portion, a handle pivotally secured to said valve to permit of lateral swinging, and a cap

mounted on said handle telescopically engaging the upper edge of said cup when the valve is seated and clearing said edge to swing laterally when the valve is removed from its seat.

In testimony whereof I affix my signature.

WILLIAM GRIKSCHET.
